UNITED STATES PATENT OFFICE.

HARRY W. KARN, OF PITTSBURGH, PENNSYLVANIA.

ARTIFICIAL LIMB.

1,244,612.

Specification of Letters Patent. Patented Oct. 30, 1917.

Application filed December 6, 1916. Serial No. 135,316.

To all whom it may concern:

Be it known that I, HARRY W. KARN, a citizen of the United States, residing at Pittsburgh, in the county of Allegheny and State of Pennsylvania, have invented certain new and useful Improvements in Artificial Limbs, of which the following is a specification.

This invention refers to improvements in artificial limbs, more especially an artificial articulated leg, consisting of an upper thigh portion adapted to form a receiving connecting receptacle for the stump of the human leg, and having a lower portion pivotally connected to turn at the knee joint.

The improvement consists in mechanism by which the lower limb member may be operated on its pivot by the user, and the invention is constructed and adapted to operate in the manner more fully hereinafter described.

Referring to the drawings:—

Figure 1 is a general view in elevation showing the device as applied to the body.

Fig. 2 is an enlarged vertical sectional view showing the compound leg member detached.

Fig. 3 is a cross-sectional view indicated by the section line III, III of Fig. 2.

Fig. 4 is a detail face view of the front portion at the knee joint, as relaxed.

Fig. 5 is a perspective detail view showing a modification.

Fig. 6 is a sectional detail view and

Fig. 7 is a perspective view showing further modified arrangements of the actuating cord mechanism.

The artificial leg members A, B, are of generally usual construction, made of wood or other suitable light strong material, the member A having at its upper portion a receiving terminal α adapted to fit closely around the stump of the amputated limb and to be held thereon by the tension of the supporting and connecting elements, hereinafter described.

The lower member B is pivotally connected by bolt 2 with the upper member A in a well-known manner whereby the two members are articulated to provide the knee joint. The lower outer front portion of the upper member A is rounded as indicated at 3 and fits neatly within the upper front edge portion 4 of the member B, providing for a small overlapping extension of each member at varying positions.

The terminal member A, rounded as stated, is vertically recessed as indicated at 5, 5, providing vertically arranged rounded grooves extending inwardly beyond the rounded surface 3 and providing by their bottoms 6 easy sliding bearings for the connecting cords 7. These cords, passing through the grooves 5 and bearing on the bottoms 6 thereof, are supported by the inner bearing portions 8, preferably slightly reinforced for strength, and are essentially fulcrum supports for the actuating cords 7.

I prefer to provide two such cords 7, as shown, each of which is connected at the rear middle or calf portion of the lower leg member B, as indicated at 9, so that when the cords 7 are relaxed the member may fall to a vertical position as indicated in Fig. 2. When the cords 7 are drawn upwardly the member B may be erected or raised into longitudinal alinement with member A.

Another advantage in having a pair of lifting cords 7 is that in case either one breaks the efficiency of the mechanism is not materially impaired and will continue to operate satisfactorily.

As indicated in Fig. 4, grooves 5 and cords 7 are normally covered by an outer sheathing or covering 24 of canvas, leather, or other suitable finishing material adapted to provide a smooth exterior to the members of the artificial limb.

Each cord 7 is provided at its upper end with a grooved sheave pulley 10 pivoted at 11 in a carrying bracket 12 which is connected at 13 to the upper end of cord 7, with suitable tension. For the purpose of so connecting cords 7 and their connecting sheaves 10 with upper shoulder-actuated operative mechanism, I use a pair of cords 14, each of which is provided at the front with a ring or other suitable connecting device 15, and at the back with a similar ring or connecting device 16. Cords 14, being continuous from each such ring 15 to the other ring 16, are thus free to engage with varying degrees of tension the sheaves 10 and to exert a pulling action on one or the other of cords 7 independently.

For the purpose of thus transmitting independent active tension to one cord 7 or the other, I utilize independent suspender straps or braces 17 and 18, respectively, adapted to pass over the left and right shoulder respectively of the wearer, as shown

in Fig. 1, and provided with suitable devices for taking up slack, as buckles 19. Each cord 14 is preferably passed through a suitable keeper or guiding and retaining loop 5 device 20 at the front and 21 at the back upper portion of the main upper limb member A so as to retain the cords in operative position on the outer portion of the limb at front and back. Suitable holes 22 and 10 23 at front and back respectively are provided through which cord 14 passes from the outside to the interior of the leg at front and back for the purpose of engaging sheave 10, as will be readily understood.

15 In Fig. 5, I show a modified arrangement in which the pair of cords 14' are extended bodily downwardly across the front portion of the knee joint and the vertical grooves 5 therein. The cords 14' engage sheave 20 wheels or pulleys 10' pivoted in carrying brackets 12' having short cords 7' connected to back or calf portion of the section B' as indicated at 9'.

The construction and operation otherwise is generally the same as above described.

25 In Figs. 6 and 7, the construction is the same as that shown in Fig. 2, except that in place of the sheave 10 I use a terminal open ring 10" through which the cord 14" passes freely, avoiding the necessity of a sheave or pulley wheel. The several other parts of the device are similarly indicated by corresponding numbers, double primed.

30 The construction and operation of the device will be readily understood from the foregoing description. Shoulder braces 17 and 18, are actuated, either one or the other, by the user, by raising one shoulder or the other, thereby exerting a lifting tension and 35 effecting the tightening of either cord 7. This upward pulling action throws the lower leg member B outwardly in a forward direction in the act of walking, and lowering of the shoulder correspondingly effects 40 lowering of the limb by gravity to a natural position of repose. A special advantage in providing the double connections is that

either shoulder may be used continuously or both shoulders may be used alternatively, thereby avoiding undue fatigue so that the 50 user may accomplish the expected functions of the device without special or tiresome effort.

What I claim is:—

1. An artificial limb consisting of upper and lower articulated members, a flexible element connected with the lower of said members, and a flexible element passing through the front and back portion of the upper member, having movable connection with said element and having terminal connecting devices, said first named flexible element passing over a rigid bearing portion in the upper of the articulated members adjacent its connection with the lower member. 60

2. An artificial limb consisting of upper and lower articulated members, a cord attached to the lower of said members and bearing against the upper member below its outer surface passing into said member and provided with a terminal sheave wheel, and an actuating cord engaging said sheave wheel and passing through the front and back portion of the upper member and provided with terminal connecting devices. 70

3. In combination, an upper hollow limb member adapted to embrace the stump of the human thigh and provided with a vertically grooved perforated knee portion, a lower hollow leg member pivoted to the 80 terminal of said upper member, a cord attached to the rear portion of said lower member passing through the grooved perforated part of the upper member and provided with a terminal sheave wheel within 85 said upper member, and an actuating cord engaging said sheave wheel and passing freely through perforations in the front and back portions of the upper member and provided with terminal connecting devices. 90

In testimony whereof I hereunto affix my signature.

HARRY W. KARN.
